APPARATUS FOR BREAKING AND LIFTING LINING BODIES

Aldo Lorenson, Noel Pertuiset, and Gerard Victor Reinhardt, all of Arvida, Quebec, Canada, assignors to Aluminium Laboratories Limited, Montreal, Quebec, Canada, a corporation of Canada

Filed Feb. 25, 1959, Ser. No. 795,412

8 Claims. (Cl. 294—67)

This invention relates to apparatus for freeing and removing an adherent solid body, for example, a massive body of lining material, from an enclosing open-topped shell, and more particularly to breaking apart and lifting a half or other portion of such body of lining material from the shell, under circumstances where the body portion to be broken away is adapted to be engaged at opposite side regions thereof, in localities accessible between the body and the shell.

In the electrolytic production of aluminum in reduction cells of conventional character, usually called pots, the material lining the pots is introduced as paste and solidified in place, and gradually hardens; after some time it fails and must be removed. These linings may vary somewhat in composition and arrangement; a common example comprises a thick inner layer of carbon and an outer, thermal insulating layer of a suitable refractory, the whole gradually assuming a monolithic character over the life of the pot. The shell is usually a steel plate structure, externally braced, and having a complete arrangement of bottom and side walls, against which the lining is packed and becomes adherent. Considerations of size and weight often require for convenience that as part of the act of removal, the complete body of lining be broken in half or other parts; thus it is desirable to break off and lift, simultaneously, the first such half or other portion, and then to remove the remaining half or portions in similar manner. It will be understood, however, that the improved apparatus described below can be used, in appropriate cases as with small pots, for removing whole linings, as well as for breaking apart and lifting half portions or portions greater or less than a half.

To prepare the lining for the specific breaking and lifting operation mentioned above, one end and the adjacent half of each side are freed by a pneumatic tool from the enclosing pot shell, exposing the steel collector bars embedded in the bottom of the pot (in the carbon portion) at right angles to its length; these bars are then severed from the shell at their juncture therewith, as by an acetylene torch, leaving engageable extensions protruding from the body of the lining. The bottom of the lining, of course, at this point still adheres to the bottom of the shell, and the partially freed half of the lining is still united with the unfreed half.

The removal of the body of the lining thus prepared, therefore, involves the application of an upward force on it in such way as to break it from the other portion and to free it from the shell, since it is desirable not to disturb the permanent installation of the shell on the potroom floor or other foundation. Conventionally the operation of breaking and lifting the lining has been effectuated through the application of direct force of an overhead crane, suitably attached to the collector bar ends. However, this method is attended with considerable hazard and inconvenience, since the lining sometimes fails to break, in which case the entire lining and shell are lifted together. A crane whose safe working load limit is sufficiently high to allow it to lift the halves of lining

separately thus may nevertheless become overloaded when the lining fails to break; moreover, in this contingency further and difficult operations are required to effect the breaking and removal of the lining.

It is therefore, an object of the present invention to provide a safe, simple and efficient means of separating and lifting such lining portion from an enclosing shell, using force exerted by an overhead crane, yet avoiding the difficulties explained above, especially in respect to displacement of the shell along with the entire lining.

Another object is to provide such lifting means for breaking and removing a body of lining with relatively limited lifting force, as by a novel arrangement of levers affording a sufficient mechanical advantage, for example, to enable a crane whose safe working load limit is not substantially greater than that necessary to accommodate the weight of a half of a body of lining (i.e. a crane substantially lighter than would otherwise be required) to effect the freeing of the lining without overloading; a special object being the provision of new lining removal apparatus wherein the distribution of forces exerted by the crane is such that the shell is held down while the lining within is broken and lifted, both to render the freeing operation more facile and to obviate the possibility of the shell being lifted. Further objects of the invention will appear in the detailed description of its structure and operation hereinbelow.

The invention in one important embodiment comprises a frame, resting on the shell from which the material is to be removed; a pair of levers, respectively pivoted on portions of the frame extending beyond the shell, disposed upwardly and inwardly therefrom, and connected at their free ends with an overhead crane or other appropriate lifting means; and engaging means respectively pivotally dependent from the levers at a point intermediate the pivot and the free end of the lever, such engaging means being attached to the body to be lifted on opposite sides thereof, and so disposed on the levers as to afford a suitable mechanical advantage for the lifting means. These elements, in combination, are so constructed and arranged that upon application of a simultaneous upward force on the levers by the lifting means, a simultaneous upward force of appropriate magnitude is applied on both sides to the body of material to be lifted, and an opposite downward force is exerted through the frame as fulcrum on the enclosing shell, these opposite forces effecting the separation and lifting of the body from the shell.

The construction and operation of the invention will be more fully explained in the description below, taken with the accompanying drawings, wherein:

Fig. 1 is a perspective view, somewhat simplified, of an aluminum reduction cell or pot containing a body of lining material such as the invention may be adapted to remove;

Fig. 2 is a top plan view of the pot of Fig. 1, with a portion of the lining broken away to illustrate an arrangement of collector bars therein and showing a further portion of the lining freed from the pot shell, as in preparation for removal by the invention;

Fig. 3 is a side elevational view of one important embodiment of the invention, somewhat simplified, showing the apparatus in position for lowering to engage the body of lining in the pot;

Fig. 4 is a side elevational view of the apparatus of Fig. 3, showing it in engagement with the lining during the lifting thereof;

Fig. 5 is a top plan view of the apparatus of Fig. 3; Fig. 6 is an enlarged detail view along the line 6—6 of Fig. 4;

Fig. 7 is a further enlarged detail view, in section along the line 7—7 of Fig. 6;

Fig. 8 is a plan view of one lever arm of the apparatus of Fig. 3;

Fig. 9 is a side elevational view of the arm of Fig. 8;

Fig. 10 is an enlarged detail view, in section along the line 10-10 of Fig. 9; and

Fig. 11 is a view in section along the line 11-11 of Fig. 3.

In its embodiment here shown by way of example, the invention is adapted to remove from an aluminum reduction pot shell 20 (Fig. 1) a body of lining 22 adherent thereto and partially freed from the shell along its sides (Figs. 2, 3 and 4) so as to provide for engagement of the apparatus with the lining, specifically by breaking the lining in half and lifting the separated halves from the shell or otherwise breaking the lining in portions and lifting the broken portions. It will be understood that the illustrated proportional relationships of various elements of the apparatus are intended to serve only for exemplification, and are not intended to be limitative of the invention.

As shown in Figs. 3, 4, 5 and 11, the apparatus includes a horizontally elongated frame, generally designated 26, adapted to rest transversely on an aluminum reduction pot, and comprising two steel bars 27, each constructed by welding a pair of channel bars together, and held in fixed, rigid, parallel spaced relation in a horizontal plane by end plates 28, the bars 27 being so dimensioned that the long axis of the frame is substantially longer than the short axis of the width of the pot shell 20. Support bars 29 extend transversely between and are rigidly connected to the bottom portion of the bars 27 at intervals along their length; within the channel bars 27 at either end thereof are vertical reinforcing plates 32 rigidly attached to the sides of the bars. Along the bottom of each bar 27 at either end thereof is rigidly attached an I-bar or I-beam section 30, mounted parallel to the bar 27, and respectively adapted to seat on and extend outwardly from the side top edges 21 of the pot shell when the apparatus is in position for removing lining. The pairs of I-bars at the respective mutually adjacent ends of the bars 27 are held in spaced relation to each other by transverse, vertically disposed spacing plates 74.

Attached to each I-bar section is a dog stop 31, fitted around and extending vertically downward from the bottom transverse flanges of the I-bar, and adjustably disposed to abut the adjacent outer side edge of the pot shell when the I-bars are resting on the shell edges 21. The stops 31 are adjustable, to be clamped at various positions along the I-bars 30, so as to fit various widths of pots. Also included in the frame structure is a pair of parallel plates or lugs 33 attached respectively to the centers of the bars 27, i.e. intermediate their ends, extending upwardly from the bars. To extend between these plates, and through suitable holes in them, there may be inserted a horizontally transverse removable bolt 34 (Figs. 3 and 5), held in place by a nut 35, and adapted to be engaged by a crane hook 75 for carrying the apparatus when not in use. Horizontal handle rods 36 extend along and respectively outside the bars 27, and horizontal handle rods 37 extend along and respectively outside the end plates 28, these handle rods or bars being rigidly attached to the frame at intervals along their length.

At either end of the frame there is mounted a shaft 38, extending transversely between the bars 27, and through and beyond the bars and the reinforcing plates 32, i.e. so that the ends of each shaft respectively protrude for a short distance outside the bars; into these protruding ends cotter pins 39 are inserted to hold the shaft in place. The shafts 38 are disposed on the frame 26 so that their axes are respectively outside the sides of the pot shell when the apparatus is in position for removing the lining.

Pivoted on each shaft 38 between the bars 27 is a lever arm, generally designated 40 (see also Figs. 8-10), extending for a considerable distance inwardly of the pivot between the bars. Each arm 40 is thus mounted to swing upwardly and outwardly when the bolt 34 is removed

from its position transversely above the levers, and is prevented from downward rotation by the transverse support bars 29. Each of these levers has a portion 41 adjacent the pivot shaft comprising a pair of channel members or bars 43, 44 held in fixed spaced relation parallel to each other in a plane containing the pivot shaft, by a base plate 45 beneath the channel bars 43, 44, and a spacing plate 46 between their upper flanges. Within the channel bars 43, 44 of each lever arm 40, near the end of the arm, a pair of vertically disposed reinforcing plates 47 are rigidly attached to the webs of the channels. At an inward position in each lever arm a pair of vertical support plates 47' are rigidly attached in parallel relation to the sides of bars 43, 44, respectively bearing holes having a common axis parallel to the shaft 38. The vertical walls of each lever arm 40 are rounded at their outer ends, i.e. at the ends nearest the pivot 38, by a semicircular contour for the protruding portions of the plates 47 and of the webs of the channels 43, 44, to permit the aforementioned rotation of the levers without hindrance by the frame end plates 28. Each lever has also an elongated portion 42 comprising the extension of channel bar 43, to which is welded a parallel section of channel bar 48, the latter being connected to channel bar 44 by diagonal channel bar section 49, for structural rigidity.

Extending vertically upward from the end of each lever 40 most distant from the pivot shaft is a plate or lug 50, rigidly attached between channel bars 43 and 49, its plane faces parallel to the long axis of the frame 26. The lug 50 bears in its upward extension a hole 51, through which a hook or other suitable part of a chain sling (not shown) may be passed and connected with an overhead crane. The levers 40 as constructed have identical orientation of the long channel bar 43 with respect to the top and the pivot end; e.g. as viewed from above (Fig. 5), looking along the lever from the pivot end, the channel bar 43 is on the left in both of the levers 40. Thus as the levers 40 lie between the bars 27 of the apparatus frame 26 in opposed relation their elongated extensions 42 are respectively on opposite sides of the long axis of the frame. That is, the extensions 42 are parallel to each other, fitting neatly within the frame 26, with the lifting lug 50 of each lever substantially nearer to the pivot of the other lever than to its own lever point, so that as the levers are rotated upwardly and outwardly they are seen from the side to cross at a point above the frame, as shown in Fig. 4. It will be appreciated that although other arrangements might be used in some cases, this disposition of the levers 40 is of special significance; it permits the use of levers of greater length than would otherwise be possible, with resultant improvement in mechanical advantage, as hereinafter explained.

Intermediate the pivot shaft 38 and the lifting lug 50 on each lever, within the section 41 adjacent the pivot shaft, and substantially nearer the pivot shaft than the plate, a transverse shaft 52 is carried in the holes of the support plates 47', being thus disposed for free rotation between the channel bars 43, 44. To this shaft (Figs. 9 and 10) there is rigidly attached a metal loop or strap 53, e.g. by a set screw 54 accessible through a hole 55 in spacing plate 46. This strap or loop 53 supports, through an aperture in the base plate 45, a depending series of plate links 56, 57 loosely pivoted to each other (with slotted pivots as shown in Figs. 6 and 7) and having plane faces parallel to the end plates 28, i.e. at right angles to the long axis of the frame 26. Each chain of plate links terminates in a grappling plate 58, disposed parallel to the plate links and thus parallel to the side of the pot shell when the apparatus is in position thereon. The grappling plate 58 (Figs. 6 and 7) has a horizontal series of three apertures 59 which are adapted to engage the protruding ends 25 of collector bars embedded in the lining, and which have notch-like lower portions 59' whose inner surfaces are case-hardened and shaped in

sharp ridges 59" to engage the collector bar ends 25 securely, i.e. to prevent slippage. The pivot shafts 52 are so disposed on the levers that the series of plate links 56, 57 and grappling plates 58 vertically dependent therefrom respectively pass between the freed sides 23 of the body of lining and the pot shell 20 when the apparatus is in position for removing lining.

When lining is to be removed from an aluminum reduction pot with the apparatus described above, the lining 22 is first laterally freed or partly freed from the pot shell 20, preferably along one end, and most especially along half of each adjacent side, with a pneumatic tool; the exposed collector bars 24 embedded in the bottom of the lining transverse to the long axis of the pot are severed at their junctions with the shell by an acetylene torch. The apparatus, with bolt 34 in place and the levers 40 resting parallel to each other in opposing position within the frame 26, is brought, by means of an overhead crane wose hook 75 engages bolt 34, into position over the pot, i.e. with the long axis of the frame parallel to the collector bars and transverse to the long axis of the pot, over the freed portion 23 of the lining, as shown in Fig. 3.

The apparatus is then lowered by the crane onto the pot shell, guided manually by the handles 36, 37, so that the I-beam sections 30 rest respectively on opposite side top edges 21 of the pot, and so that the dog stops 31 respectively abut the outer side edges of the pot, fixing the apparatus in position over the pot. The grappling plates 59 are thus lowered between the respective freed sides of the lining and the shell walls, and are brought manually into respective engagement with three adjacent collector bar ends 25 by fitting the bar ends into the grappling plate apertures 59. After removal of the crane hook, the bolt 34 is removed to permit upward rotation of the levers 40, and a double chain sling or the like is hooked to or otherwise passed through the apertures 50 at the extremity of each lever.

The sling being connected to the crane, upward movement of the crane cables or chains draws the levers 40 simultaneously upward, exerting a simultaneous upward force on both sides of the lining through the engagement of collector bar ends 25 with grappling plates 58. At the same time, there is exerted a simultaneous downward force on both sides of the shell through the frame 26, which acts as fulcrum for the levers. Continued upward motion of the crane thus pulls the lining upward, freeing it from the bottom of the shell, and most importantly, breaking it from the unfreed half of the lining, while the downward force exerted on the shell by the frame as fulcrum effectively obviates the danger of the shell being lifted along with the lining.

That is to say, the breaking apart and the detachment of the lining from the shell is effected with certainty and in a simple operation; while by appropriate arrangement of the levers, i.e. in disposition of the grappling pivot shafts or lead points 52 and of the sling apertures or force points 51 with respect to the lever pivot shafts or fulcrums 38, a high mechanical advantage is achieved, enabling the employment of a relatively light crane for the operation. In one particular case, the ratio of the distance 51-38 to the distance 52-38 was 8:1.5, affording a mechanical advantage of greater than 5.3; a crane with a safe working load limit of 15 tons thus was enabled to provide, within its safe limit, a lifting force of 40 tons through each lever on each side of the lining, for a total upward force of 80 tons, thereby safely and easily detaching the lining from the pot, whereas without the apparatus the crane could safely provide an upward force only of 15 tons, frequently insufficient to break the lining free. The use of the adjustable dog stops to secure the apparatus from slipping off the frame during removal of the lining, and the peculiar configuration of the grappling apertures 59 to prevent slippage

of the collector bars, add a further feature of safety to the operation.

When the lining has been freed from the shell, the apparatus appears as in Fig. 4, with the levers disposed upwardly and inwardly from their pivot points, and the body of lining suspended securely from the levers, on the grappling plates. Further upward motion of the crane lifts the lining free of the shell, and the lining, still engaged in the apparatus, may be without further adjustment transported to another location as desired. The apparatus can, of course, then be utilized for removing the remaining body or bodies (i.e. half or other portions) from the shell, in similar fashion.

Thus the apparatus achieves the safe and convenient removal of bodies of lining from aluminum reduction pots, utilizing the upward force of a crane to provide opposite forces on the lining portion and the pot shell through an appropriate arrangement of levers on a frame and thus to effect positive breaking and detachment of the lining from the shell; multiplying the force of the crane with a high mechanical advantage achieved through appropriate arrangement of the levers, to enable the use of a far smaller crane than would otherwise be necessary for the operation; and holding the lifted lining body securely to permit facile transportation thereof by the crane from the shell to another location.

It is to be understood that the invention is not limited to the specific devices herein disclosed but may be embodied in other forms without departure from its spirit.

30 We claim:

1. Apparatus for lifting from an enclosing open-topped shell, a body of material which is engageable at transversely spaced, opposite regions thereof, comprising frame means having transversely spaced portions respectively 35 adapted to rest on opposite parts of the shell that are adjacent to but outside said regions of the body, a pair of levers pivoted to the frame means at localities respectively adjacent said portions, each lever extending upwardly and transversely toward a point above the pivot locality of the other lever, means at the upper ends of 40 the levers for applying lifting force simultaneously thereto, and a pair of grappling means respectively connected to the levers at localities thereof spaced from the pivot localities and from the force-applying means, and engageable with the said body at said opposite regions thereof, for exerting lifting force thereon.

2. Apparatus for lifting from an enclosing open-topped shell, a body of material which is engageable at opposite sides thereof within the shell, comprising frame means 50 adapted to rest on opposite edges of the shell and having portions extending respectively beyond the shell, a pair of levers respectively pivoted to said portions and extending upwardly and inwardly from the frame means, means at the upper ends of the levers for applying lifting force simultaneously thereto, and a pair of grappling means respectively depending from the levers at intermediate localities thereof and adapted for lifting engagement with the aforesaid opposite sides of the said body.

3. Apparatus as defined in claim 2, wherein the frame means includes stop means depending from the outer portions of said frame means and adapted to extend below the aforesaid edges of the shell, to engage opposite side regions of said shell for preventing lateral displacement of the frame means.

65 4. Apparatus as defined in claim 2, wherein the frame means is shaped to receive the levers in substantially horizontal position for storage of same when the upper ends of the levers are relieved of lifting force.

5. Apparatus for lifting, from an enclosing open-topped shell, a body of material which is engageable at opposite sides thereof within the shell, comprising a frame adapted to extend across the shell in seating abutment with opposite edges thereof, said frame including parts extending outwardly of the shell at both sides, a pair of levers respectively pivoted to the outwardly extending parts of the

frame, said levers being disposed to extend upwardly and inwardly from their said pivots, in crossing relation at a locality above the frame, and said levers extending beyond the locality of said crossing relation and having means at their upper ends for applying lifting force simultaneously thereto, and a pair of grappling means respectively connected to the levers at localities near to and inward of the aforesaid pivots, said grappling means respectively depending from their said localities of connection to the levers and having means at their lower ends for engaging the aforesaid opposite sides of the body of material, said frame, levers and grappling means being mutually constructed and arranged so that upon seating of the frame on the shell and upon engagement of the grappling means with the body of material, lifting force on the upper ends of the levers will cause the levers to pull the body of material upward relative to the shell.

6. Apparatus as defined in claim 5, wherein the frame includes stops respectively depending from the outer parts of said frame and adapted to extend below the aforesaid edges of the shell, for engaging opposite side regions of said shell to prevent lateral displacement of the frame, and wherein the frame is constructed to provide an elongated open-topped recess therein for receiving the levers

in substantially horizontal position for storage of same when the upper ends of the levers are relieved of lifting force.

7. Apparatus as defined in claim 6, which includes means including retaining structure removably disposed across said recess, for holding the levers against substantial upward displacement when the apparatus is not in use for lifting, said holding means being constructed to constitute means for applying suspending force to the apparatus to transport it.

8. Apparatus as defined in claim 5, wherein each of the depending grappling means comprises a chain composed of links mutually movable, within limits, lengthwise of the chain, and wherein the engaging means at the lower end of each grappling means comprises a grappling plate having an apertured configuration for engaging structure projecting from a side of the aforesaid body of material.
